AUTOMOBILE JACK

Arthur J. Belanger, 3216 Sanford St., Muskegon, Mich.
Filed May 31, 1963, Ser. No. 286,106
9 Claims. (Cl. 254—105)

This invention relates to a hoist mechanism, especially a vehicle hoist or jack, and more particularly to a chain-lift hoist.

This application is a continuation-in-part application of my copending application entitled Automobile Jack, filed June 26, 1962, Serial No. 205,278 now abandoned.

Various types of chain hoists have been devised heretofore. Since the chain is a flexible and highly adaptable tension element, it is advantageous to use. As far as is known, however, none has ever gained wide acceptance for use as a vehicle jack. Heretofore, it has been difficult, if not impossible to achieve a simple, manual drive means for the chain to enable a large mechanical advantage to be obtained without a complex winching action. Further, as far as is known, no really satisfactory method of controllably reversing movement of the chain has been possible on a small scale for lowering the vehicle on the jack or hoist.

It is therefore an object of this invention to provide a compact, chain hoist mechanism enabling simple, manual operation while also achieving a large mechanical advantage.

It is another object of this invention to provide a chain hoist enabling smooth operation as a vehicle jack, thereby providing the jack with the flexible characteristic of a chain without the operating difficulties and reverse movement difficulties experienced heretofore.

It is another object of this invention to provide a roller-chain hoist having an easily controlled reverse action in eccentric element. Further, the eccentric is controlled in the amount of binding force which it applies to the roller chain due to a control element operable between the eccentric and its mounting bracket.

It is still another object of this invention to provide a chain hoist having an easily controlled reverse action in a link by link manner by the use of magnetic actuating means mounted on the handle of the jack.

These and many other objects of this invention will be apparent upon studying the following specification in conjunction with the drawings in which:

FIG. 1 is a side elevational view of one form of the novel jack or hoist during hoisting operation, and showing the eccentric and handle being shifted in an upward movement just before moving downwardly to lift the hoist mechanism;

FIG. 2 is a fragmentary, side elevational view of the apparatus in FIG. 1 after the eccentric and handle is in the upper-most position and the handle is being lowered to raise the chain hoist mechanism;

FIG. 3 is a front elevational view of the apparatus taken in the direction of III as indicated by the arrow in FIG. 2;

FIG. 4 is a fragmentary, side elevational view of the hoist apparatus during the lowering operation, showing the link by link release of the chain;

FIG. 5 is a top sectional view taken on plane V—V of the apparatus as illustrated in FIG. 4;

FIG. 6 is a fragmentary, elevational view of the end of the hoisting chain showing a slightly modified operation thereof;

FIG. 7 is a fragmentary, perspective view of the end of the chain hoist showing a still different modified operation;

FIG. 8 is a fragmentary, perspective view of a modified form of the jack;

2

FIG. 9 is an exploded perspective view of the modified jack;

FIG. 10 is a fragmentary side elevational view of the modified jack;

5 FIG. 11 is a fragmentary side elevational view of the modified apparatus with the chain being disengaged from chain catch hook; and

FIG. 12 is an enlarged fragmentary view of the chain link cam and a chain link.

10 Basically, the inventive hoist mechanism comprises a support, a sprocket means rotatably mounted on the support, a hoisting roller chain around the sprocket, and a handle-operated eccentric mounted adjacent the sprocket and chain, and adapted to be shifted into engagement with the chain between adjacent rollers to shift the chain around the sprocket a limited amount. The eccentric is pivotally mounted on a bracket, which is in turn pivotally mounted to the upper end of the vertical support or stand. The eccentric includes a lobe movable into engagement between adjacent rollers on the sprocket. Further shifting of the handle shifts the chain and sprocket a predetermined amount. Catch means on the stand holds the chain in its shifted position with each reciprocation of the handle and eccentric. The engagement force of the eccentric on the chain roller is limited by a roller element between the eccentric and its mounting bracket, causing a binding action after the engagement between the eccentric and roller chain occurs. Before this binding occurs, the handle and eccentric move with respect to the bracket. After the binding the handle and bracket move as a unit.

20 The hoist apparatus also includes a unique lowering or reverse action release mechanism including a lifting pin means. This lifting pin is actuated by the actuation means on the handle during upward movement of the handle. The pin shifts the individual rollers around the chain catching hook to enable a link by link lowering. The actuating means on the handle is preferably a magnet which shifts the releasing pin means a predetermined amount to release one link of the chain, and then break loose from the releasing pin means to allow the next roller of the chain to catch on the hook.

25 Referring now to the drawings, in the form of the invention illustrated in FIG. 1, the novel hoist apparatus 10 includes a support means 12, a hoisting chain means 14, and an eccentric mechanism 16.

30 The support or stand 12 preferably includes a cylindrical sleeve 18 which interfits telescopically with a cylindrical element 20 projecting upwardly from base 22. The upper end of the cylindrical stand is machined away to provide a slot and a pair of spaced ears 26 and 28 illustrated in FIG. 3. Between these ears extends a central pin 30 upon which sprocket 32 is fixedly mounted. The teeth of this sprocket project between the adjacent rollers 34 of roller chain 14. The rollers are interconnected by side links in a conventional manner.

35 On the front end of the roller chain 14 is provided a hook 42 for hoisting purposes. This hook may interfit with an inverted U-shaped bracket 46 welded or otherwise suitably affixed to the lifting support 48. The lifting support is integral with a cylindrical guide sleeve 50 which surrounds the stand 18 and moves vertically up and down on it. Upon the upper surface of this support 48, an automobile bumper 54 may be placed for hoisting purposes. To alleviate frictional contact between cylindrical sleeve 50 and stand 18, a pair of diagonally located rollers 56 and 58 are provided.

40 The opposite end of the chain may pass through a suitable opening 60 (FIG. 3) into the cylindrical stand 18 for proper storage of any chain slack as the chain is moved back and forth around the sprocket 32.

45 Movement of the chain and sprocket is effected with

the eccentric mechanism 16. This eccentric includes a lobe 70 beneath the pivotal pin 72 where the eccentric is pivotally mounted on the vertically extending bracket 74. This bracket includes two downwardly extending legs 76 and 78 pivotally mounted on pin 30, and includes an upper cross member or surface 80 i.e. a top. The pin 72 extending between the legs of this bracket pivotally mounts eccentric 16. Integral with the eccentric is a handle 84. If desired, the handle may be telescopically extendible, utilizing sleeve 86 and retaining pin 88 in slot 90 to provide additional mechanical advantage in an obvious manner. By movement of handle 84 within the bracket 74, the lobe 70 of the eccentric 16 can be placed into engagement with the chain between adjacent rollers 40, or out of engagement therewith to allow movement of the handle over the rollers as illustrated in FIG. 1.

The pressure of the lobe 70 on the rollers of the chain is limited by the binding action which occurs between the roller element or ball 96 inserted between the portion of eccentric 16 opposite lobe 70, and the top surface 80 of bracket 74. Bracket 74 pivots independently of the sprocket 32. Roller member 96 is retained in the housing by downwardly depending front and rear flanges 100 and 102 on bracket 74. It rests in a recess adjacent tang 106 of the eccentric.

The hoisting chain 14 is held in any position by hook 108 which is integral with stand 18, and projects slightly downwardly as illustrated in FIGS. 1 and 2. Even with the weight of an automobile (see bumper 54) on support 48, the chain will not allow the sprocket 32 to rotate counterclockwise until the chain rollers are released from this catch hook 108.

During the hoisting operation of the apparatus, handle 84 is rotated downwardly. It first moves with respect to bracket 74 to cause an engagement between lobe 70 and a pair of adjacent rollers 40 as illustrated in FIG. 2. The binding force of this engagement is limited by the ball 96 which binds between the upper surface of the eccentric and the top surface 80 of bracket 74 illustrated in FIG. 2 when the handle is rotated further. Additional downward rotation of the handle 84 in the direction of the arrow illustrated in FIG. 2 then causes the bracket 74 to also rotate about its pivotal shaft 30 to thereby rotate the chain and sprocket in a clockwise fashion around pin 30. As it does so, another chain roller 40 moves over hook 108 and catches therebeneath to prevent reverse movement of the chain.

When the handle is again lifted (FIG. 1), it rotates with respect to the bracket to move lobe 70 out of engagement with rollers 40 and also release the binding action between ball 96 and the upper surface 80 of the bracket 74. After it rotates a small amount the eccentric abuts flange 102 and causes the entire bracket to pivot upwardly and counterclockwise as well as the handle and eccentric. Thereby, the handle can be pivoted and the bracket can be pivoted counterclockwise into its original position illustrated in FIG. 2 to enable another downward movement of the eccentric apparatus. The uppermost position of the handle and bracket can be determined by a stop 81 on the bracket (FIG. 1) which abuts the ear 78 of the stand 18. The handle is repeatedly reciprocated until the object is hoisted the desired amount by travel of support 48 up stand 18.

Reverse movement of the apparatus to lower the hoist is accomplished as the result of two specific actions. First, the individual rollers 40 of the chain must be released one at a time from beneath the retaining catch means or hook 108. Also, movement of the chain in reverse direction must be manually controlled by eccentric 16 and handle 84 to prevent a jumping action under the weight of the vehicle.

The first action, i.e. the release of the individual rollers from around hook 108, is achieved through a special lifting or hoisting pin 114 (FIG. 5) which is adapted to

extend between the rollers 40 to enable lifting of each roller one at a time around the hook. This pin 114 includes a portion extending through opening 116 in cylinder 118 (portion 120) to serve as a guide, a retracting means, and an extension limit means. A tension spring 122 is secured between the inner end of this portion 120 and a screw 124 extending across the cylinder 118 to retract the pin. A washer 132 retained on portion 120 by a pin or cotter key 134 limits the extension of the pin. Pin 114 also includes a loop-shaped projection 130 which enable activation of the pin hoist by actuation means 138 on handle 84. The releasing pin 114 and its extension 130 are extendible to the position illustrated in FIG. 4 against the bias of spring 122 until washer 132 abuts the inner surface of the cylinder 118.

The actuation means 138 is preferably a magnet mounted to a handle by a suitable bracket 140 and bolts 142. During the normal hoisting operation, a keeper 150 is placed across the poles of the magnet 138 as illustrated in FIG. 1. Thus, the magnet normally does not actuate the pin releasing means during the upward movement of the handle 84. When it is desired to lower the hoisting mechanism, i.e., cause the chain and sprocket to move in a counterclockwise direction as illustrated in FIG. 4, the keeper 150 is removed from magnet 138. Then, as handle 84 is lowered, the magnet comes in contact with extension 130 of the pin release. As the handle is raised again (as illustrated in FIG. 4), the magnet pulls the pin release upwardly and outwardly until washer 132 contacts the inner wall of the cylinder 118. As the pin 114 is raised upwardly and outwardly, it lifts a roller 40 of the chain around hook 108 to allow that roller to be released for counterclockwise movement of the chain. As soon as the magnet has reached the position illustrated in FIG. 4, and the washer 132 abuts the cylinder 118, further movement of the handle causes release of the magnet from the extension 130 thereby causing the spring 122 to retract the releasing pin 114. This initial releasing action occurs with the ball 96 at the front of bracket 74 as illustrated in FIG. 4. At the time the magnet releases portion 130, however, the ball 96 rolls against ear or tang (see arrow FIG. 4) 166. Lobe 70 is engaged between two adjacent rollers 40 to allow the operator to manually control the rate at which the chain and the sprocket move counterclockwise to lower the vehicle. On the next downward stroke of the handle, the operator prevents the binding action between the eccentric 16, ball 96 and upper surface 80 of the bracket 74 to thus prevent the lobe 70 of the cam from engaging between the rollers. This is done by keeping the handle in its most counterclockwise position with respect to the bracket 74 while rotating the handle and bracket clockwise. On the downward movement of the handle, therefore, no hoisting occurs. Magnet 138 then comes in contact with extension 130 again to repeat the lowering step, a link at a time.

Operation of the apparatus as explained with respect to the particular structure above is thus obvious from this prior description. Briefly, when an automobile illustrated by bumper 54 is to be hoisted, it is placed above support 48. Keeper 150 is placed on magnet 138. Handle 84 is reciprocated vertically, i.e. in alternate clockwise and counterclockwise directions to rotate sprocket 32 clockwise. During the hoisting operation, the handle is first deliberately rotated clockwise with respect to the bracket 74 to engage the lobe 70 with the rollers 40 and binds the ball 96 between the eccentric and the bracket. This engagement is released in the upward reverse direction. Alternatively, when lowering the hoist, i.e. causing the sprocket and chain to move counterclockwise, the lobe 70 is purposely prevented from engaging the rollers 40 on the downward movement, i.e. the handle and eccentric are retained in their counterclockwise position with respect to the bracket 74 on the downward movement, and on the upward movement, lobe 70 is purposely engaged

with the rollers. Since the weight of the vehicle tending to move the chain in a counterclockwise direction will tend to force the handle upwardly and the operator's hand will be pushing downwardly on the handle, the handle eccentric will be in the clockwise most position with respect to the bracket to control the downward movement of the chain.

Instead of the apparatus being used in the form illustrated in FIG. 1 with the support 48 directly onto the hook 42, the hook 42 may be used directly on a bumper 54 as illustrated in FIG. 6. Alternatively, the U-shaped inverted bar 46 may be provided with a roller 180 fitting between the side links of the chain 14 as illustrated in FIG. 7. In this form of the invention, not only will the bumper 54 rest on the support 48, but also the chain will pass around the roller 180 and hook 42 will engage the top of bumper 54 to hold it in a secure manner. Thus, raising of the chain illustrated in FIG. 7 will cause movement of the chain along roller 180 to give a smooth controlled hoisting or lowering of the vehicle. Obviously, various other forms of securing the chain hoist to the particular article to be hoisted or lowered may be utilized.

Modified Apparatus

Referring to FIGS. 8 through 12, a modified and preferred form of the apparatus using a mechanical cam to release the chain, instead of the magnetic releasing means, is illustrated. The novel modified jack 200 includes a suitable base, an upright support 202, a pivotal handle bracket 204, and a camming handle 206 similar to those in the previously illustrated form.

The upright 202 includes a pair of oppositely positioned vertical slots 208, in which the chain sprocket 210 fits to be rotatably mounted on transverse pin 212. The pin is rotatably supported on upright post 202 in a pair of opposite openings 214, 90° removed from slots 208. The roller chain 220 includes suitable bumper hook means (not shown in FIG. 8 but similar to the previous type shown) attached to end 220' of the chain. The other end of the chain is slack, and may be positioned within the hollowed post 202 through a suitable orifice 224. The roller chain passes over the top of sprocket 210 as previously.

Bracket 204 has a pair of spaced openings 230 and 230' in the lower ends of its legs to be pivotally mounted upon pin 202 extending through the top of the post. The bracket also includes a pair of openings 234 near its upper end to receive cylindrical pin 236, also inserted through opening 238 in the eccentric head 240 on the end of handle 206. The opening 238 is mounted off the center line of eccentric 240, to cause the lower eccentric surface 240' to move into engagement between a pair of links of the roller chain, or out of engagement therewith when the handle is pivoted upon pin 236.

The head normally fits between the legs of the generally inverted U-shaped support bracket 204. Thus, the handle may be pivoted with respect to the bracket, and the bracket may be pivoted with respect to the post, as necessary. Pivoting of the handle moves the eccentric into and out of engagement with the roller chain, while pivoting of the bracket enables a "bite" to be obtained on the chain when the handle is depressed for engagement of the eccentric with the roller chain. The top of the eccentric 240 includes a recess 250 within which a ball 252 fits in order to lock the handle with respect to the bracket 204 as described with respect to the previous modification.

Protruding from the surface of cylindrical pin 212 is an engagement tooth 260 which fits within slot 262 cut into the periphery of the post opening 214. The slot is provided with an arcuate width somewhat greater than the width of element 260, to allow a slight amount of play between the cylindrical pin and the slot. Also, the opening 230' on one side of bracket 204 includes a wide arcuate slot 232 cut into its periphery to receive a control

stop 270. The control stop lever 270 has a cylindrical shank 272 which fits within a special opening 274 in connecting pin 212 to allow rotation of the control stop on a 90° angle using its handle 276. The arcuate width of slot 232 is substantially greater than the width of stop 270 to allow bracket movement with respect to the special stop 270, for taking repeated "bites" on the jack using handle 206.

It will be observed that surface 280 of stop 270 is displaced from the rotational anchoring shank 272 a greater distance than surface 282 which is removed 90° from surface 280. Consequently, by rotating stop 270 using handle 276, either surface 280 or surface 282 may be alternatively placed to abut the end surface 290 of slot 232 in bracket 204, thereby limiting the arcuate bracket movement to two different values. The operation will be more specifically described hereinafter.

Positioned beneath slot 208 is a chain hook catch 298, as previously, to anchor the chain and prevent it from moving when a load is applied thereto.

Mounted to post 202 by pivotal elements 300 is a special U-shaped cam 302 having its legs straddling the post for pivotal connection thereto, and having a special toe 304 with a curved concave frontal surface especially adapted to interfit with one of the chain rollers 306 as shown in FIG. 12. When rotational camming element 302 is pivoted to its down position on orientation (as illustrated in FIG. 9), it is out of engagement with the roller chain. When, however, the pivotal cam is rotated upwardly to a position toward horizontal (i.e. clockwise in the form of the invention illustrated in FIG. 9), the concave surface on toe 304 engages one of the rollers (as illustrated in FIG. 12) to push the roller chain outwardly away from the post 202 and around hook catch 298 as the chain lifts the cam, to allow the chain to move in a reverse direction for lowering a load on the end 220' of the chain. The cam 302 includes an ear 310 projecting therefrom for engagement with a stop bar 312 protruding from the post 202. Engagement of this ear 310 with the stop bar 312 limits the upward movement of the cam element 302 and thus of toe 304 to a position below the horizontal plane. At this position the roller chain is moved past the catch 298 sufficiently to allow one roller link to move past the catch. At this time, the mechanism allows the next adjacent roller link to become engaged with the catch, as the weight of the load upon the chain automatically pulls the chain out of engagement with the concave toe 304, allowing the camming element 302 to drop down to its downwardly biased position by its weight.

When a load is to be raised on the end 220 of the roller chain by the jack assembly, as illustrated for example by the arrow in FIG. 8, the handle 206 is first rotated clockwise (FIG. 8) with respect to bracket 204 to disengage the eccentric surface 240' from the roller chain. The handle is then raised further to rotate bracket 204 with respect to post 202 and around pin 214 to enable a "bite" to be obtained on the chain. The handle is then lowered in the bracket to cause the eccentric surface 240' to engage between two of the rollers of roller chain 220. Depression of the handle from the position illustrated in solid in FIG. 8 to the handle axis shown by the phantom line 205' in FIG. 8 forces the roller chain around sprocket 210 with rotation of the sprocket on pin 212. This causes an adjacent roller link to move around the slightly downwardly curved ear catch 298 and catch thereunder. This hoists the item the length of one chain link.

When something is to be thus hoisted, control stop lever 270 is pivoted on its shank 212 so that handle 276 protrudes outwardly away from the jack assembly at approximately 90° as shown in FIG. 8. At this position, the stop surface 280 (FIG. 9) is in a position to abut surface 290 of slot 232 of bracket 204 (FIG. 9).

It will be seen that tooth 260 positively engaging slot 262 in post 202 prevents surface 290 in slot 232 of the

bracket from rotating stop 270 and pin 212 when force is applied therebetween, as it would if this positive engagement of tooth 260 with its respective slot 262 were not present.

The phantom line illustrated in FIG. 8 at 206' is the lowermost position of handle 206 when hoisting something, since contact of surface 280 with surface 290 limits the downward handle movement. At this position, the lower edge of bracket 204 is not low enough to form an operative abutting engagement with ear 310 on cam 302. Thus, to take another bite on the jack and hoist the mechanism one further link, the handle is lifted again to move eccentric surface 240' out of engagement with the roller chain and then rotate bracket 204 on pin 212 with respect to post 202. The handle is lowered again. This process is repeated until the article is at the desired height.

To lower the article on the jack in a closely controlled manner, first control stop 270 is rotated 90° so that hook 276 lies alongside bracket 204 (as illustrated in FIGS. 9, 10 and 11). In this position, the contacting surface of the stop is 282 to abut surface 290 of slot 232 at the lowermost position of the handle. It will be noted that since surface 282 is substantially closer to the pivotal axis of the shank of stop 270, bracket 204 may be rotated counterclockwise further than it could when hoisting something. This puts the handle and bracket in a lower position.

To lower an article, therefore, the handle is first placed in the position illustrated in FIGURE 10 to put bracket 204 in the position illustrated in FIGURE 10, usually almost vertical. The handle is then lowered to rotate the bracket and cause its lowered edge to contact ear 310 of special, rotational, U-shaped chain shifting cam 302 (FIG. 11). The handle and bracket are then depressed further to rotate the cam in a clockwise direction (as viewed in FIG. 11). At this position the concave surface 304 on the toe of the cam is in operative engagement with one of the rollers 306 on the chain as shown in FIG. 12. Lifting of the handle to move the eccentric 240 out of engagement with the chain, thereby allows the force on the chain to move the chain and cam slightly upwardly. The upward movement of this portion of the chain (see arrow in FIG. 11) causes the roller to carry the cam 302 with it, thereby rotating it in a clockwise direction around its pivotal mount 300. This causes the ear 304 to move away from post 202 and simultaneously shift the roller chain away from the post and temporarily out of engagement with its holding catch 298 until one of the roller links passes by the hook. Further, rotation of the chain and cam 302 causes engagement of ear 310 with stop 312 so that the weight of the load on the chain forces the chain to disengage from the slightly concave surface to toe 304. This enables the cam 302 to drop down against the post, and allow the chain to move inwardly again so that the next roller link engages behind the catch 298.

After the chain has moved past the hook one link, this process is repeated again and again by merely lowering the handle again to rotate the cam 302 outwardly into engagement with the next adjacent link, etc.

It has been found that the novel jack works completely dependably and effectively for hoisting automobiles, and buildings, as examples. It has remarkable leverage to enable its use safely and effectively wherever desired.

Various additional modifications of the apparatus, within the inventive principles taught may be apparent to those in the art upon studying the foregoing forms. These obvious modifications are deemed to be part of this invention, which is to be limited only by the scope of the appended claims, and the reasonably equivalent structures to those defined therein.

I claim:

1. A vehicle jack comprising: a vertical support; a sprocket rotatably mounted adjacent the top of said support; a roller hoisting chain adapted to pass over the top

of said sprocket and including hoisting means on one end; a bracket extending above said sprocket and adapted to oscillate on said support; an eccentric rotatably mounted on said bracket adjacent said sprocket and chain; said eccentric having a lobe movable into engagement between adjacent rollers of said chain on said sprocket; handle means protruding from said eccentric enabling movement of said lobe into engagement with said chain with further rotation of said eccentric causing shifting of said chain around said sprocket; chain catch means on said support to hold said chain in its shifted position; a rolling element between said bracket and a portion of said eccentric opposite said lobe; said rolling element being movable to a first position to bind between said bracket and eccentric when said eccentric is shifted into engagement with said chain to thereby cause said eccentric, handle, and bracket to shift together, and movable to a second position to be free from binding when said eccentric and chain are out of engagement, to allow said handle and eccentric to shift with respect to said bracket.

2. A hoist mechanism comprising: a support; a sprocket rotatably mounted on said support; a hoisting roller chain around said sprocket; an eccentric mounted adjacent said sprocket and chain and adapted to be shifted into engagement with said chain between adjacent rollers thereof to shift said chain around said sprocket; a handle on said eccentric; catch means on said support adapted to secure said chain when shifted; and release means mounted on said support, and operably associated with said handle and shiftable therewith to release a section of said chain from said catch means with each oscillation of said handle to allow reverse movement of said chain on said sprocket.

3. The mechanism in claim 2 wherein said catch means is a hook, and said release means is a biased pin adapted to move under rollers of said chain when shifted, to shift them off said hook.

4. The apparatus in claim 3 wherein said pin is shiftably actuated by actuating means on said handle.

5. The apparatus in claim 4 wherein said actuating means is a magnet on said handle in operative relation to said pin to actuate said pin and release rollers of said chain one by one around said hook.

6. A hoist mechanism comprising: a support; sprocket means on said support; a roller chain around said sprocket means; manual chain shifting means including a handle; chain catch means on said support in operative engaging relation to said chain; means on said support, shiftable to release said chain from said catch means; and a magnet on said handle positioned to shift and actuate said release means.

7. A hoist mechanism comprising: a support; a sprocket rotatably mounted on said support; a hoisting roller chain around said sprocket; an eccentric mounted adjacent said sprocket and chain, positioned adjacent said chain, and movable toward and away therefrom to be shifted into engagement with said chain between adjacent rollers thereof to shift said chain around said sprocket; a handle on said eccentric to shift it; catch means on said support adjacent said chain to engage and secure said chain when the chain is shifted by said eccentric and handle; and release means adjacent said catch means, operable with movement of said eccentric and operably engageable with said chain to shift and release a section of said chain from said catch means with each oscillation of said handle and eccentric to allow reverse movement of said chain on said sprocket; said release means comprising a cam element pivotally mounted to said support and engaging said roller chain only temporarily to shift it out around said catch means and being configurated to be releaseable therefrom after shifting said chain out around said catch means, to return to its initial position.

8. A vehicle jack comprising: a vertical support; a sprocket rotatably mounted adjacent the top of said support; a roller hoisting chain adapted to pass over the top of said sprocket; a bracket extending above said sprocket

and adapted to oscillate on said support; an eccentric rotatably mounted on said bracket adjacent said sprocket and chain; said eccentric having a lobe movable into engagement between adjacent rollers of said chain on said sprocket; handle means protruding from said eccentric enabling movement into engagement with said chain, and rotation of said eccentric causing shifting of said chain around said sprocket; and chain catch means on said support to hold said chain in its shifted position; a chain release cam element pivotally mounted to said support 10 and having a chain engaging surface; said cam element being engageable by said bracket to rotate the cam element into operative engagement with said chain to release the chain temporarily from said catch means.

9. The jack in claim 8 wherein a variable control stop 15 is positioned between said bracket and support and mov-

able between first and second positions therebetween to cause binding therebetween and hoisting action in said first position of said stop, and to release the binding condition therebetween and cause lowering action in said 5 second position.
